UNITED STATES PATENT OFFICE.

PERCY H. THOMAS, OF MONTCLAIR, NEW JERSEY, ASSIGNOR, BY MESNE ASSIGNMENTS, TO COOPER HEWITT ELECTRIC CO., OF HOBOKEN, NEW JERSEY, A CORPORATION OF NEW JERSEY.

CIRCUIT-INTERRUPTER.

1,079,380.

Specification of Letters Patent.

Patented Nov. 25, 1913.

Original application filed December 24, 1906, Serial No. 349,270. Divided and this application filed April 24, 1908. Serial No. 428,965.

To all whom it may concern:

Be it known that I, PERCY H. THOMAS, a citizen of the United States, and resident of Montclair, county of Essex, State of New Jersey, have invented certain new and useful Improvements in Circuit-Interrupters, of which the following is a specification.

This application is a division of a certain application filed by me, December 24, 1906, Serial Number 349,270, relating to methods of and apparatus for starting vapor devices; and the special subject of this application is a circuit interrupter constituting a part of the apparatus described and shown in the 15 said prior application.

In order to serve the purpose of the particular invention described in my above mentioned prior application and also for many other purposes, it is desirable to provide a 20 circuit interrupter in which the action at the moment of rupturing the circuit at the interrupter shall be very positive and sudden and as well, able to resist a shock of high potential. That is to say, it is important in 25 the special case referred to and in many other cases that a circuit interrupter should be provided wherein the formation of an arc at the moment of separation of the interrupter terminals should be avoided and a 30 clean, positive, absolute break be accomplished.

By the devices which are illustrated and described herein, I am able to accomplish these results, as has been satisfactorily demonstrated in actual practice. It will be understood that to properly perform its functions, it is usually desirable that the device be exhausted of air and other impurities and that all occluded gases be eliminated from 40 the solid and liquid bodies within the vacuum space, and also that it be inserted in a circuit carrying a current low in strength or otherwise rendered unstable.

In one form of the apparatus, the contacting parts between which a rupture takes place for the interruption of the circuit consist of mercury and in another form these parts consist of solid elements, one of which is stationary and the other movable. In 45 both forms of apparatus the contacting and separating parts are within a hermetically sealed and completely exhausted container with trunnions on which the said container

may be turned for the purpose of causing the separation or contacting of the terminals 55 of the interrupter, as the case may be. The forms adapted are such as have been found particularly well suited to the causing of a quick and complete interruption of the circuit inside the container.

The details of the circuit interrupter herein claimed are illustrated in the accompanying drawings, in which—

Figure 1 is a longitudinal section through one form of the apparatus; Fig. 2 is a cross 65 section along the line 2—2 in Fig. 1, looking toward the left; and Fig. 3 is an elevation of a modified form of circuit interrupter. Fig. 4 shows circuits adapted to supply unstable current to one of applicant's circuit 70 interrupters.

Referring more particularly to Figs. 1 and 2, 1 is a container, generally cylindrical in form, and provided with axial trunnions, 2 and 3, on which the device may be caused 75 to rock or rotate. The lower part of the cylinder is distorted by an indentation, 4, which forms in the inside of the container a ridge, 5, adapted to separate the interior of the container at its lower side into two 80 pockets, 6 and 7, wherein mercury is adapted to be contained as is clearly shown in the drawing. The normal position of the circuit interrupter at times when the circuit is closed through it is one in which this ridge 85 stands at an angle of approximately forty-five degrees to the horizontal, at which time, as shown in Fig. 2, the mercury is connected over the lower part of the ridge so that there is a complete conducting contact between 90 the mercury in one pocket and that in the other. By turning the device on its trunnions slightly toward the observer, as the device appears in Fig. 1, the mercury is caused to separate over the lower edge of 95 the ridge, much as if a knife-edge of insulating material had been thrust between the mercury in the two pockets. It is found that the rupture which takes place under these conditions is clean cut and positive 100 and causes an absolute rupture of the circuit under ordinary conditions of use. Connection from the outside to the mercury in the two pockets 6 and 7, is obtained by means of circuit wires, 8 and 9, 105 passing down through reentrant tubes, 10

and 11, and having leads, 12 and 13, which are sealed into and through the lower ends of the said tubes. The connection of the circuit interrupter, (which in practice has 5 come to be denominated a shifter), upon a circuit in which it is included is obvious. It will often be found desirable, as shown in the figure, that the cylindrical portion of the container, the trunnions, the indented portion and the reëntrant tubes, should be of glass 10 and should all be formed of the same material integral with one another and of relatively the same thickness, on account of the greater facility in handling and annealing of the material.

In Fig. 3 the cylinder, 14, is mounted on trunnions, 15 and 16, which are at right angles to the axis of the cylinder. The contacting parts are shown at 17 and 18, the former being loosely suspended so as to rest against the stationary contact part, 18, when the device is resting on its trunnions in a certain position as shown, and to swing so as to fall away from contact therewith 25 when the device is turned away from the observer. The terminal, 17, is hung in this instance upon a hook, 19, which is provided with a lead, 20, passing through and sealed into the upper end of the cylinder.

The stationary contact part, 18, is connected 30 to a lead, 21, sealed into and passing out from the lower end of the cylinder.

The device of Fig. 3 is specially suitable when transportation conditions are severe as it is not subject to shock from mercury 35 violently thrown about during transportation.

I claim as my invention:—

A circuit interrupter, comprising a hermetically sealed and completely exhausted 40 glass chamber having a body part substantially cylindrical in form with hollow axial extensions at the ends, a quantity of mercury within the container, an indentation in the cylindrical part of said container 45 adapted to divide the mercury into two parts on rotation about the axial extensions and reëntrant tubes inclosing lead wires and introducing the lead wires under the surface of the divided bodies of mercury, together 50 with seals for said lead wires.

Signed at New York in the county of New York and State of New York this 23rd day of April A. D. 1908.

PERCY H. THOMAS.
